UNITED STATES PATENT OFFICE.

WILLIAM ARTHUR SCOTT, OF PORTLAND, OREGON.

PHONOGRAPH SOUND-BOARD.

1,369,845.

Specification of Letters Patent.

Patented Mar. 1, 1921.

Application filed May 7, 1920. Serial No. 379,601.

To all whom it may concern:

Be it known that I, WILLIAM A. SCOTT, a citizen of the United States, and a resident of Portland, in the county of Multnomah 5 and State of Oregon, have invented certain new and useful Improvements in Phonograph Sound-Boards, of which the following is a specification.

My invention is an improvement in phonograph sound boards, and has for its 10 object to provide a device of the character specified, wherein the volume of tone is increased while the quality of the sounds being reproduced is retained, the sound board 15 being combined with the amplifier and forming a part thereof.

In the drawings,

Figure 1 is a perspective view of the improved amplifier with parts broken away,

Fig. 2 is a diagrammatic view of a phonograph showing the position of the amplifier.

The present embodiment of the invention is shown in connection with a phonograph having the usual casing 1, and the sound 25 board forms the lower wall of the amplifier which is shown more particularly in Fig. 1. This amplifier is a funnel-shaped structure 2 having at its small end a tubular structure 3 which connects the said small end with the 30 tone arm 4 of the phonograph, and the sound vibrations pass from the tone arm to the tubular structure and to the amplifier body to be discharged into the air.

The amplifier has three of its walls, 35 namely the top and side walls, composed of wood or any other suitable material, and the fourth wall is composed of a sheet 5 of plate glass, the said sheet being triangular as shown to correspond with the shape of 40 the said wall.

A false bottom or wall 6 is arranged below the sheet 5, the said false wall or bot-

tom being spaced apart from the sheet 5 by strips 7 which are arranged near the side edges of the sheet and bottom, and the false 45 bottom is secured to the side walls of the amplifier by means of screws or the like 8.

Referring to Fig. 1, it will be seen that the sheet 5 is shaped to close the lower side of the amplifier, and the said sheet has an 50 extension portion 9 which passes into the tubular extension 3 and fills the bottom thereof. A block 10 is seated on this extension, and abuts the rear wall of the tubular extension 3, and it will be noticed 55 that the upper face of the block is concaved, and rounded so that it acts to deflect the sound waves from the tubular extension into the amplifier. The spacing of the sheet 5 from the sheet 7 or false bottom provides a 60 layer of dead air between the two sheets, and this column of air vibrates, assisting the amplifier in the manner of a resonator under a marimbaphone bar. The improvement increases the volume of tone, while retaining 65 the quality of the instrument and in reproducing the voice, when it is the voice, it also adds to the clearness and distinctness of the words being spoken.

I claim:

An amplifier comprising a body of pyramidal form arranged in substantially horizontal position, an upright tubular member formed at the smaller end of the body, a false bottom disposed below the bottom of 75 the body, strips disposed near the side edges of the body between the bottom thereof and the false bottom whereby to space away the latter and form a relatively long and wide but thin air space, and securing members 80 passing through the false bottom outwardly of the edges of the bottom of the body into the lower edges of the sides of the body.

WILLIAM ARTHUR SCOTT.
